(57) CLAIM

The ornamental design for a box containing shaving products, as shown and described.

DESCRIPTION

FIG. 1 is a first perspective view of an ornamental design for a box containing shaving products according to the present invention;

FIG. 2 a second perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof

FIG. 9 is a first perspective view of another embodiment of an ornamental design for a box containing shaving products according to the present invention;

FIG. 10 is a second perspective view thereof;

FIG. 11 is a front view thereof;

The back view, the left and right views, and the top and bottom views of the second embodiment are the same as those from the first embodiment.

The broken line disclosure of the box illustrates the environment. The remaining broken lines illustrate background portions of the design of the shaver and of the shaving blade cartridge. None of the broken lines forms part of the claimed design.

FIGS. 1-3, 5-6 and 9-11 show that the box has a lighter stipple shading representing a first color and a darker stipple shading representing a second color, which is different than or contrasting the first color.
